UNITED STATES PATENT OFFICE.

HALSEY W. WILSON, OF MINNEAPOLIS, MINNESOTA.

PRINTER'S CHASE.

1,266,366.

Specification of Letters Patent.

Patented May 14, 1918.

Application filed May 4, 1910. Serial No. 559,383.

To all whom it may concern:

Be it known that I, HALSEY W. WILSON, of Minneapolis, Hennepin county, Minnesota, have invented certain new and useful 5 Improvements in Printers' Chases, of which the following is a specification.

The object of the invention is to provide a chase wherein the tops or heads of the pages on one side of the sheet may be adjusted in 10 perfect register and uniform margins with the pages on the other side of the sheet without the necessity of adjusting the top to the extent that is usually required in chases as ordinarily formed. Generally in the old 15 style of printers' book chase the quoins are placed around the outside and pressure is toward the center of the chase from the four sides, bars being used only to stiffen the chase and support the type in the center and 20 to keep it from falling out when the chase is moved and prevent the side bars from bending.

Considerable difficulty has been experienced with the old form of chase, as it was 25 absolutely necessary that every page should be of exactly the same length and it was found that when the forms were locked up, particularly if wood furniture was used, that there would be quite a little compression in the form and the heads of the pages 30 would be found to be out of alinement with one another.

My invention consists generally, therefore, in a chase having cross bars, the edges 35 of which form seats for the heads of the pages of type, and when these heads are once set against the bars it is immaterial if some of the pages of type are shorter than others. A suitable amount of furniture will be 40 used for the short pages, but the heads of the pages will constantly remain in alinement and the pages on opposite sides of the sheet will register perfectly with one another.

45 In the accompanying drawings forming part of this specification,

Figure 1 is a plan view of a chase embodying my invention,

Fig. 2 is a modified construction in which 50 the cross bars are divided longitudinally, forming a comparatively large middle chase, and smaller ones on each side thereof.

In the drawing, 2 represents the side rails of the chase and 3 the end rails, all of metal. 55 4 and 5 are cross bars fitting within dove-tailed notches 6 and 7, which are arranged

in pairs on each side of the middle portion of the chase. These dovetail notches coöperate with the cross bars to prevent the side rails from spreading in a comparatively 60 large chase adapted for receiving sixteen or thirty-two pages, where the side rail is from 42 to 60 inches in length and seldom, if ever, less than 38 inches. This type of chase is used on a cylinder press in book or magazine work and it is quite important to have the side rails locked in parallel relation to one another. I am able to accomplish this by means of the cross bars and at the same time these bars fix the position of the heads 65 of the pages in the form. 8 and 8' represent pages of type, the former full length pages and the latter short pages. The heads of all the pages are, as shown, seated against the edges of the bars 4 and 5. 9 and 10 70 are pieces of furniture and 11 locking quoins interposed between the pieces of furniture and forcing the pages against the edges of the bars. The short pages have an additional piece of furniture 12, and at the sides 75 of the chase furniture 13 and 14 is employed and between the pages suitable pieces 15 and 16 are arranged. The space between the bars 4 and 5 is sufficient to accomodate two rows of pages, each having its head 80 bearing on the inner edges of the bars and held in contact therewith by the quoins. Furniture strips 17 are interposed between the bars and the heads of the pages to provide a margin of the desired width. These 85 strips can, of course, be varied, according to the margin desired. The distance between the bars is preferably twice the distance between the bars and the contiguous end of the chase and as the chase is preferably made of such size to accommodate four 90 pages in a row, it follows that sixteen pages may be printed on one side of a sheet of paper, such as is usually used in book work, and the heads of all these pages, owing to 95 100 the method of locking them outwardly against the bars instead of toward the center of the chase, will be in perfect alinement with one another across the chase and when the other side of the sheet is printed, its 105 pages will register perfectly with those first printed on the sheet. The adjustment of the bars in the dovetailed slots 6 and 7 adapts the chase for variation in the standard sizes of book paper, and compensation 110 may be made for the desired variation in the margins at the heads of the pages, as

before stated, but the strips of furniture placed at the heads, being of uniform width, will not affect in any way the register of the opposite pages.

5 The bars 4 and 5 are normally stationary, the heads of all the pages of type are seated against the longitudinal edges of these bars, consequently the heads of all the pages in the same row will be in perfect alinement 10 with one another regardless of the length of the page, and when these pages are removed from the chase and others substituted, if the substituted pages are also seated against the longitudinal edges of the bars with the furniture 15 16 between the pages, it must also be evident that when the sheet of sixteen pages is printed on both sides the opposite pages will be in perfect register with one another, and no accurate adjustment or 20 measuring or fitting will be required.

In Fig. 2 I have shown a modified construction which consists in forming the chase in three parts—a middle chase 18 and side chases 19 which, when assembled, form 25 one of the size shown in Fig. 1 and having the same functions, the pages being locked in alinement with one another at the top and in perfect register. This chase, however, can be handled easier than the other 30 form, as the parts are separable. I am thus able to obtain an accurate register of the pages on the opposite sides of the sheet and perfect alinement of the heads of the pages and practically no adjustment or fitting is

required to assemble the pages and lock 35 them in the form.

I claim as my invention:—

Means for laying out and locking-up type-page forms for printing comprising a book-chase consisting of a frame having parallel sides and parallel end members, and stiff bars rigidly tying one side of the frame to the opposite side and dividing the space embraced within the four outside members of the chase into divisions separated from each other by the cross bars so disposed that the heads of the type-pages will lie next to the cross bar separating one division from the other and permit the insertion of locking means at the feet of the type-pages, with some of the locking means inserted between the frame and feet of the type-pages and others between the adjacent feet of type-pages placed end to end, and additional locking means between the sides of the type-pages and side of the frame, to press the heads of two type-pages each toward the other and also press the several type-pages from one side of the frame toward the opposite side.

In witness whereof, I have hereunto set my hand this twenty-third day of April, 1910.

HALSEY W. WILSON.
